PAVEMENT BREAKING EQUIPMENT

Charles O. Finn, Cincinnati, Ohio, assignor to
Nove Engine Company, Lansing, Mich., a corporation of Michigan

Application November 19, 1936, Serial No. 111,712

12 Claims. (Cl. 262—13)

This invention relates generally to apparatus for demolishing concrete or other types of pavement and refers more particularly to apparatus of this character embodying the drop hammer principle.

One of the principal objects of this invention is to simplify, render more efficient, and reduce the cost of equipment of the above type by providing a construction sufficiently compact and light in weight to permit readily supporting the same on a relatively small low capacity truck chassis.

Another object of this invention resides in the provision of a truck attachment of the character set forth which is sufficiently light in weight to permit the several parts thereof to be mounted as a unit on a relatively light, fast truck, and which is equipped with a hammer possessing the weight required to effectively break up pavement.

A further feature of this invention resides in the provision of a pavement breaker, equipped with a gravity actuated hammer having a removable nose capable of being readily interchanged for different types of nose pieces or for a cutting device designed to trim certain types of pavement.

In addition to the foregoing, this invention contemplates an attachment having a vertically extending guide for the hammer movable from an upright position perpendicular to the chassis frame to a position substantially parallel to the latter. This feature is advantageous in that it provides for obtaining the necessary clearance above the vehicle during transportation of the equipment, and also permits storing the vehicle in a building of normal size.

With the foregoing, as well as other objects in view, the invention resides in the novel construction of the pavement breaking equipment and this construction will be made more apparent as the description proceeds, especially when considered in connection with the accompanying drawings, wherein:

Figure 1 is a perspective view of a truck chassis having pavement breaking equipment constructed in accordance with this invention;

Figure 2 is a fragmentary side elevational view of the construction shown in Figure 1 and illustrating the vertical extension in its folded position;

Figure 3 is an end elevational view of the pavement breaking equipment showing the drop hammer in its raised position;

Figure 4 is an enlarged side elevational view of the drop hammer assembly;

Figure 5 is a cross sectional view taken substantially on the plane indicated by the line 5—5 of Figure 4;

Figure 6 is an end elevational view of the drop hammer showing a cutting device in association therewith; and

Figure 7 is a side elevational view of the construction shown in Figure 6.

In Figure 1 of the drawings, I have shown my improved pavement breaking equipment as mounted on a relatively small capacity truck chassis 10 in rear of the driver's cab 11. The truck chassis illustrated is a standard 1½ ton model, and my improved equipment may be supported on the frame 12 of the chassis without altering, or otherwise interfering, with the original design or construction of the chassis. In accordance with conventional practice, the frame 12 comprises longitudinally extending laterally spaced side sills 13 suspended from the rear axle 14 of the truck in the usual manner by suitable semi-elliptical springs 15. The forward end of the frame 12 is suspended from the front axle of the vehicle by suitable springs (not shown), and the motor for propelling the truck, as well as the driver's cab 11, is supported on the forward end of the frame 12.

The pavement breaking equipment is shown in the several figures as having a base in the form of a frame 16 embodying longitudinally extending side sills 17 secured together in lateral spaced relationship at the front and rear ends by cross members 18 and 19, respectively. The side sills 17 are spaced from each other a distance corresponding to the lateral spacing of the side sills 13 of the chassis frame 12, and are supported directly upon the sills 13 in the manner clearly shown in Figure 3. In the interest of rigidity, the side sills 17 are in the form of I beams, and the transverse members 18 and 19 are substantially channel-shaped in cross section. The ends of the cross members extend laterally outwardly beyond opposite sides of the frame 16 and are preferably welded to the ends of the sills 17 to provide an integral construction. Any suitable means may be resorted to for securing the frame 16 in assembled relation with the chassis frame 12 and, in the present instance, this is accomplished by bolting the bottom flanges of the sills 17 to the top flanges of the sills 13 forming structural parts of the chassis frame 12.

The drop hammer 20 of the equipment is supported for vertical sliding movement on the frame 16 rearwardly of the axle 14 and midway between the rear ground engaging wheels 21.

mounted on the extremities of the axle 14. With this arrangement, the hammer is permitted to fall into engagement with the road surface without interference from any part of the truck chassis. In the present instance, the hammer is guided throughout its vertical movement by means of a pair of vertical stanchions 21' and 22 secured at their lower ends to the frame 16 in lateral spaced relationship. It will be observed from Figure 5 that the stanchions are substantially channel-shaped in cross section and are secured to the frame 16 with the channels opening outwardly.

In order to provide for reducing the height of the stanchions when the equipment is being transported by the truck, each of the stanchions is formed of two sections 23 and 24. It will be observed from Figure 1 that the upper ends of the lower sections 23 are secured together in proper spaced relationship by means of a frame 25 having longitudinally extending outwardly opening channel members 26 interconnected at the rear ends by means of a transverse member 27 rigidly secured to the free ends of the rear cross member 19 of the frame 16 by means of the diagonal braces 28. The members 26 extend forwardly on opposite sides of the stanchions and are rigidly secured to the outer sides of the latter by means of the spacers 29. The forward ends of the side members 26 extend beyond the corresponding sides of the stanchions and are connected by means of a hinge pin 30. The hinge pin, in turn, is connected to a frame 31 similar to the frame 25 and secured to the lower ends of the sections 24 of the stanchions, with the result that the upper sections 24 may be swung from the vertical position thereof shown in Figure 1 to the horizontal position of the same illustrated in Figure 2. It will be noted from the latter figure that the sections 24 are supported in a horizontal position from the frame 16 by a standard 32 secured to and extending upwardly from the frame 16. In detail, the forward ends of the longitudinal side members 33 of the frame 31 are connected to the hinge pin 30 by means of the brackets 34, and the rear cross member 35 of the frame 31 is detachably secured to the upper extremities of the diagonal braces 28 by means of the nuts and bolts 36. The side members 33 are secured to the outer sides of the sections 24 by means of the spacers 37 in order to effectively hold the lower ends of the sections 24 in proper spaced relationship, and the upper ends of the latter sections are secured together by means of a transverse brace 38 having the extremities thereof respectively connected to the opposite ends of the front cross member 18 of the frame 16 by means of the rods 39. The opposite ends of the rods 39 are readily detachably secured to their respective cross braces by means of fastener elements 40 in the form of nuts and bolts. With the above arrangement, it will be noted that the sections 24 of the stanchions are rigidly held in their upright positions and may be readily moved to the horizontal position shown in Figure 2 by merely detaching the upper ends of the diagonal braces 28 from the frame 31 and by removing the rods 39.

The hammer 20 is supported between the stanchions for sliding movement longitudinally of the latter and, as shown in Figure 5, is formed with recesses 41 in opposite sides of sufficient dimension to slidably receive the side flanges of the stanchions 21 and 22. Referring now to Figures 3 and 4, it will be noted that the sides of

the hammer 20, adjacent the sides having the recesses, are also recessed, as at 42, to receive the U bolts 43 having the lower ends projecting below the hammer 20 for attachment to the nose 44 of the hammer. The nose 44 is shown in Figures 1 to 5, inclusive, as designed to actually break pavement, although it will be understood from Figures 6 and 7 that this nose may be interchanged with a steel cutting knife 45 in the event it is desired to employ the equipment for trimming the edges of the pavement.

In the present instance, the hammer 20 is moved upwardly along the stanchions by means of a suitable hoist 46 and is permitted to drop by gravity into engagement with the pavement. The hoist 46 is of conventional construction comprising a drum 47 journaled upon the frame 16 for rotation about an axis extending transversely to the side sills 17 of the frame, and is connected to a prime mover 48 also mounted on the frame 16. In the present instance, the prime mover 48 is in the form of an internal combustion engine supported upon the frame 16 with the drive shaft thereof extending parallel to the axis of the drum and connected to an intermediate shaft 49 by the belt and pulley arrangement indicated in Figure 4 by the reference character 50. The intermediate shaft 49 is journaled on the frame 16 and is connected to the drum 47 in the usual manner by reduction gearing. It will be observed from Figure 4 that one end of the hammer actuating cable 51 is secured to the drum 47 of the hoist, and the other end is reeved around a pulley 52 supported on a cross member 53 interconnecting the extreme upper ends of the stanchions. The cable extends downwardly from the pulley and is secured to the hammer through the medium of a shock absorbing unit 54. The shock absorbing unit 54 comprises a shaft 55 supported on the hammer and connected to the free end 56 of the cable by means of the coil spring 57. As shown in Figure 3, a U-shaped clip 58 is engaged with the shaft 55 intermediate the ends of the latter, and the leg portions of the clip extend upwardly through the spring 57 and are bent over the upper end of the spring in the manner designated by the reference character 59. A similar clip 60 is assembled with the eye formed at the free end 56 of the cable, and the leg portions of this clip are extended downwardly through the spring and are bent over the lower end of the spring in the manner shown in Figure 4. With this arrangement, it will be apparent that the free end of the cable is flexibly connected to the hammer by the spring 57 and this is desirable in that it reduces the effect of the shock resulting from engagement of the hammer with the pavement.

From the foregoing, it will be noted that the equipment is actuated in the same manner as any hoist. For example, when the operator desires to raise the hammer to its uppermost position, the lever 61 is manipulated to clutch the drum shaft with the prime mover. This causes a rotation of the hoisting drum in a direction to wind the cable around the same and, as the cable is wound around the drum, the weight is moved in an upward direction along the vertical stanchions. When the weight assumes the desired elevation above the pavement to be broken, the operator merely manipulates the lever 61 to release the drum from the prime mover, permitting the weight to fall by gravity into engagement with the pavement. The weight may be held in a position spaced from the pavement by means of a

pawl 62 pivotally supported on the frame 16 and adapted to engage a ratchet wheel 63 secured to the hoisting drum. However, to avoid unduly tensioning the cable 51 during transportation of the equipment by the truck, I provide means in the form of a pin 65 for holding the hammer in a raised position. As shown in Figure 3, the pin 65 is removably supported in a pair of brackets 66 secured to the frame 16 and depending from the latter.

It will be noted from the above that I have provided a compact, mobile pavement breaker composed of a relatively few parts and capable of being readily manufactured, assembled and installed. It should also be understood that all of the parts capable of being permanently secured together are preferably welded so as to provide an integral construction. In addition, it will be noted that my improved breaking equipment lends itself to application on a relatively small capacity truck and may be installed on the latter without changing or interfering with the standard construction of the truck chassis.

I claim:

1. In pavement breaking equipment, a frame, a vertical stanchion extending upwardly from the frame and comprising aligned sections pivotally connected together to permit folding the upper section to a position wherein the height of the stanchion is reduced an amount approximating the length of the upper section, and a weight slidably engaging said stanchion.

2. In pavement breaking equipment, a frame, vertical stanchions having lower sections fixed to the frame and having upper sections foldable from an upright position in alignment with the lower sections to a position wherein the height of the stanchions is reduced by an amount approximating the length of the upper sections, and a weight slidably engaging said stanchions.

3. In pavement breaking equipment, a frame, vertical stanchions having lower sections fixed to the frame and having upper sections foldable from an upright position in alignment with the lower sections to a position wherein the height of the stanchions is reduced by an amount approximating the length of the upper sections, means for securing the upper sections in an upright position, a hammer slidably engaging the stanchions, and means carried by the frame and connected to the hammer for sliding the latter in an upward direction on said stanchions.

4. In pavement breaking equipment, a frame, vertical stanchions having lower sections secured to the frame in lateral spaced relation and having upper sections in alignment with the lower sections, means hingedly connecting the upper and lower sections permitting the upper sections to be folded to a position wherein the height of the stanchions is reduced by an amount approximating the length of the upper sections, a weight disposed between the stanchions and slidably engaging the latter, and means for holding the upper sections in alignment with the lower sections.

5. In pavement breaking equipment, a frame, vertical stanchions having lower sections secured to the frame in lateral spaced relation and having upper sections in alignment with the lower sections, means hingedly connecting the upper and lower sections permitting the upper sections to be folded to a position wherein the height of the stanchions is reduced by an amount approximating the length of the upper sections, a weight dis-

posed between the stanchions and slidably engaging the latter, means for holding the upper sections in alignment with the lower sections, and hoisting mechanism carried by the frame and operatively connected to the weight for moving the same upwardly on the stanchions and operable to permit the weight to drop by gravity into engagement with the pavement.

6. In pavement breaking equipment, a frame, a vertical stanchion extending upwardly from the frame and comprising aligned sections pivotally connected together to permit folding the upper section to a position wherein the height of the stanchion is reduced an amount approximating the length of the upper section, and a weight slidably engaging the upper and lower sections of the stanchion.

7. An attachment for a truck comprising a frame, a vertical stanchion extending upwardly from the frame and comprising aligned sections pivotally connected together to permit folding of the upper section to a position wherein the height of the stanchion is substantially reduced, and a weight slidably engaging said stanchion.

8. An attachment for a truck comprising a frame, vertical stanchions having lower sections fixed to the frame and having upper sections foldable from an upright position in alignment with the lower sections to a position substantially horizontal, a drop hammer guided by the stanchions into engagement with the pavement upon which the truck is supported, and hoisting mechanism supported on the frame for actuating the drop hammer.

9. An attachment for a truck comprising a frame, a vertical stanchion having the lower section fixed to the frame and having an upper section foldable from an upright position in alignment with the lower section to a position wherein the height of the stanchion is appreciably reduced, means for securing the upper section in aligned relation to the lower section, and a drop hammer guided by the stanchion into engagement with the pavement upon which the truck is supported.

10. An attachment for a truck comprising a frame, a vertical stanchion having a lower section fixed to the frame and having an upper section foldable from an upright position in alignment with the lower section to a position substantially horizontal, means for securing the upper section in aligned relation to the lower section, a drop hammer slidably engaging said stanchion and guided by the latter into engagement with the pavement upon which the truck is supported, hoisting mechanism supported on the frame, said hoisting mechanism including means for moving the drop hammer upwardly along the stanchion, and means for disconnecting the last named means to permit the hammer to drop by gravity into engagement with the pavement.

11. An attachment for trucks comprising a frame, vertical stanchions having lower sections secured to the frame in lateral spaced relation and having upper sections in alignment with the lower sections, means hingedly connecting the upper and lower sections permitting the upper sections to be folded to a position wherein the height of the stanchions is appreciably reduced, means for securing the upper sections in aligned relation to the lower sections, a drop hammer guided by the stanchions for movement into engagement with the pavement upon which the truck is supported, and hoisting mechanism car-

ried by the frame and connected to the drop hammer for actuating the latter.

12. In pavement breaking equipment, a frame, vertical stanchions having lower sections fixed 5 to the frame and having upper sections foldable from an upright position in alignment with the lower sections to a position wherein the height of the stanchions is reduced by an amount approximating the length of the upper sections, 10 a weight slidably engaging the vertical stanchions, means for moving the weight in an upward

direction on said stanchion including a hoisting mechanism supported on the frame, said mechanism having a hoisting drum and having a cable secured at one end to the hoisting drum, a pulley supported on the stanchion adjacent the upper end thereof and adapted to engage the other end portion of the cable, and yieldable means connecting the latter end of the cable to said weight.

CHARLES O. FINN. 10
